UNITED STATES PATENT OFFICE.

GOTTFRIED H. BINDER, OF ORANGE, NEW JERSEY.

SPOT ANCHOR.

Application filed October 14, 1927. Serial No. 226,065.

This invention relates to means for effectively securing building finishing blocks or slabs to brick or concrete supporting walls. It sometimes happens, particularly in the case of artificial building slabs, that great difficulty is encountered in selecting a cement that will effectively bind the slab to a supporting wall of brick or concrete. This is particularly true in the case of slabs of building material made in imitation of stone. In order to guarantee an efficient binding connection between the supporting wall and the blocks or slabs which are to constitute the finished surface (either interior or exterior) I have devised an efficient means in the form of an anchor on the back of the slab or block, which is so constructed as to not interfere with package or shipment by requiring more room than would be occupied by said slab or block itself, and which, is of such a character that a workman can instantly put it in condition to function as an efficient anchoring means.

In the drawings I have shown my invention in certain preferred forms, and in said drawings—

Fig. 1 is a perspective view of the rear side of a portion of a slab of building material which is designed to form the finished surface of the building, be it either interior or exterior;

Fig. 2 is a cross section showing my invention as in use;

Fig. 3 is a rear elevation of part of a slab with a modified form of anchorage means;

Fig. 4 is a cross-sectional modification.

1 represents an ordinary building wall which, in this instance, may be assumed to be of brick. 2 represents a slab of building material which is to constitute the finished facing for the wall 1. 3 represents a portion of cement by which the slab 2 is secured to the wall 1. At the back of each slab 2 I may provide one or more anchorage devices which, in the form shown in Figs. 1 and 2, may comprise a strip 4 of metal, properly secured at one end to the back of the slab 2, as by a fastening 5. 6 is a slot in the other end of the strip 4, and 7 is a stud secured to the slab 2 and standing in the slot 6.

When the material is on the ground ready to be installed the workman merely inserts the end of a screw driver or other suitable tool under the strip 4, between the fasten-

ings 5 and 7, and deformed or displaced after the manner shown at the right hand end of Fig. 1, for example, thereby forming an offset loop. When these anchorage devices are deformed in this manner, a portion of cement is applied to the back of the slab 2, so as to envelop each anchorage device, and then the slab is placed in position, as indicated in Fig. 2. Manifestly, the cement should be of a character that will adhere firmly to the rough supporting wall, and, even if it is not of a character that will adhere as firmly to the back of the finishing slab 2, it will be so firmly tied thereto by means of the anchorage devices that an effective union will be made between the supporting wall 1 and each slab 2.

It will be noted that the deformed loop 4 is somewhat springy and where the supporting wall 1 is more or less uneven or not plumb, the slabs 2 may be forced inwardly by reason of the deformable character of the loops 4, so as to produce a plumb finished wall.

In the form shown in Fig. 3 I have shown at 4^a a modification of the anchorage device in which, instead of being made of a strip of metal, said device is made of a wire bent into the form of the figure 8 and secured to the back of the finishing slab 2^a by means of a staple or other suitable fastening 8. This anchorage will normally lie substantially flat against the back of the slab, and thus not interfere with packing or shipment. When it is on the ground, ready for setting up on a supporting wall, the looped ends of this modified form of anchorage are pried up and away from the back of the slab 2^a by means of a suitable tool, so that a portion of cement may be applied to and around the anchorage. When the block or slab is in place on the supporting wall, it will be mechanically tied thereto, as in the previous case.

Broadly speaking, it will be seen that the purpose of my invention is to provide an anchorage device in connection with a block or slab of building material which, when not in use, lies substantially flat against the rear face of the slab, but which, when in use, may be so displaced as to permit a portion of the cement to envelop the same, so that, through the medium of said cement and said anchorage, the block may be very firmly united to a supporting wall.

In the modification shown in Fig. 4 it will be noted that the block 2 is recessed at the back underneath the strip 4^a, so that the cement material 3 may flow in under said anchorage strip to lock the block in place. In this particular instance, the anchorage strip 4^a may or may not be bendable to an offset position as shown in Fig. 2.

What I claim is:

- 10 1. A piece of building material, an anchorage device secured thereto and flat against the back thereof, and comprising a strip of sheet metal slidably connected at one end thereto, said device being displaceable to permit the same to be enveloped in cement or the like, said anchorage device being in the

form of a loop when offset from said piece of building material.

2. A piece of building material, a sheet metal strip secured flatwise against the back of said piece, the intermediate portion of said strip being deformable to form a loop for an anchorage for cement.

3. A piece of building material, an anchorage comprising a strip of sheet metal secured at its ends close to the back of said piece, the securing means at one end of said strip allowing said end to have limited sliding movement whereby the mid portion of said strip may be pried away from said piece to form a cement receiving cavity.
